[57] CLAIM

The ornamental design for a wall mounted aquarium, substantially as shown and described.

DESCRIPTION

FIG. 1 is a perspective view taken from the top, front and left side of a wall mounted aquarium showing my new design;

FIG. 2 is a top plan view thereof;

FIG. 3 is a front elevational view thereof;

FIG. 4 is a left side elevational view thereof, the right side being a mirror image of the left side shown;

FIG. 5 is a rear elevational view thereof; and

FIG. 6 is a bottom plan view thereof.

FIG.-1.

FIG.-2.

FIG.-4.

FIG.-3.

FIG.-5.

FIG.-6.
